CONTINUOUS LOAF FEEDING AND TIMING
DEVICERobert J. Beutel, Brooklyn, N. Y., assignor to
American Machine & Foundry Company, a
corporation of New Jersey

Application April 8, 1938, Serial No. 200,938

12 Claims. (Cl. 146—153)

This invention relates to a machine of the nature of a bread slicer, especially to such a machine intended for use in conjunction with a machine for wrapping the sliced loaves, and more particularly to the provision of means by which the operation of the slicing mechanism is so co-ordinated with that of the wrapping mechanism as to assure the uniform delivery to the wrapping mechanism of a stream of loaves responding accurately to the demand of the wrapping mechanism.

An object of the present invention is to provide improved sensing devices to furnish a reliable indication of any irregularity in the arrival of sliced loaves at the station where they are to be transferred from the slicer to the take-on element of the wrapping mechanism, and to provide means responding automatically to such indications of irregularity to correct the disconformity and restore the normal regularity of operation without requiring volitional control or special attention by the operator.

In pursuance of the foregoing general object of the invention, an object of ancillary character is to provide electrically operating switch devices in circuit with a solenoid by which the feeding of the loaves both before and after the slicing operation is controlled and so arranged that upon occurrence of any disconformity in the timing of the loaf-arrival at the outbound conveyor, when coming from the slicer mechanism, as for example when the loaf advances too rapidly, or is late in arrival, one or more of the conveyors will be incapacitated, and will be rehabilitated at the lapse of a suitable interval, adequate to permit correction of the disconformity.

Other objects and features of the invention will appear as the description of the particular physical embodiment selected for illustration progresses.

In the accompanying drawings, like characters of reference have been applied to corresponding parts throughout the several views which make up the drawings, in which:

Fig. 1 is a partial side elevation showing the driving means of a bread slicing machine;

Fig. 2 is a continued side elevation of Fig. 1;

Fig. 3 is a sectional end elevation of the planetary gearing and variable speed mechanism;

Fig. 4 is a sectional side elevation taken on the line 4—4 of Fig. 3;

Fig. 5 is an enlarged detail view of Fig. 2; and

Fig. 6 is a plan view taken from the line 6—6 of Fig. 5.

In the now-preferred embodiment of the invention selected for illustration and description, the part designated generally by the reference character 10 is the infeed conveyor of a bread-slicing machine, and cooperates with the intermediate conveyor 11 to lead the loaves of bread to a slicer mechanism whose reciprocating slicer knives 12, Fig. 1, are driven by any suitable means not shown, said conveyors being driven by a motor 13, Fig. 3, in conjunction with a vari-speed motor 10 pulley 14, having the characteristics hereinafter set forth. Pulley 14 mounted on motor shaft 15, by means of a V-belt 16 drives a pulley 17, Figs. 1 and 4, secured to one end of a shaft 18 which is mounted on roller bearings 19 provided in housing 20. A worm 21, which may be integral with shaft 18, meshes with a worm wheel 22 loosely mounted on shaft 23 and imparts motion to planetary gearing to be hereinafter described.

Shaft 23 at one end is mounted in a bearing 24 of housing 20 and its other end is supported by a bearing 25 of housing cover 26 enclosing the planetary gearing. Housing 20 has extending hubs 27, Fig. 4, providing means for suspending said housing from the rods 28 which are supported by the side frames 29 and 30 of the machine.

The rods 28 support loosely mounted across bars 31 and 32 which are spaced by a tie plate 33. The bars 31 and 32, at their base, are provided with T slots 34 adapted to receive T bolts 35 which support plate 33, said plate having extending feet 36 which carry the motor 13. In this manner the motor 13 and pulley 14 may be moved in and out to line-up the drive with pulley 17 and, when correctly set, the position is maintained by tightening nuts 37. The cross bar 31, midway of its length, is provided with a threaded aperture 38 receiving a spindle 39 having a handwheel 40, thus providing means for moving the bars 31 and 32 back and forth on rods 28, and consequently the motor 13 and pulley 14. The movement of the motor and pulley with respect to the pulley 17 changes the speed of the latter by means to be presently described.

The vari-speed motor pulley 14 may be of the type procurable in the market under the name "Reeves" and which, in the form herein illustrated, consists of two opposing cone-faced disks, one stationary, laterally, and the other sliding and which includes an adjustable compression spring, (not shown) all of which is self-contained and may be mounted on any standard motor shaft. When the motor is at the position nearest to the driven shaft 18, the V-belt 16 assumes

the largest arc of contact or diameter formed by the disks, and the maximum speed is obtained on the driven pulley.

By turning the speed control hand wheel 40, the motor is moved away from the driven pulley, causing the V-belt to assume a smaller arc of contact or diameter between the disks, the sliding disk moving laterally, but held in positive contact with the V-belt by means of the compression spring, and thus the speed of the driven pulley is reduced.

When the motor is moved to the position farthest away from the driven shaft, the V-belt assumes the smallest diameter, and the minimum speed is obtained on the driven pulley 17.

A table 41 supported by the side frames 29 and 30, is provided with an elongated slot 42, Fig. 3, permitting movement of an indicator 43 secured to the bar 31. Table 41 at its slotted portion 20 may be provided with graduated markings furnishing to the operator an indication which enables him to adjust the speed of the infeed belt with respect to that of the outbound belt which in turn is synchronized with the wrapping machine.

When the desired speed of the slicer is obtained, the speed adjusting spindle 39 becomes automatically locked in position by means of a spring tensioned ball 44 engaging in one of a number of depressions 45 provided in a collar 46 secured to said spindle.

The worm wheel 22, Figs. 3 and 4, is interlocked with a gear 50, also loose on shaft 23, and which meshes with a gear 51 interlocked with a planet gear 52, the latter being in mesh with a sun gear 53 keyed on shaft 23. Gears 51 and 52 are loosely mounted on a stud 54 supported by an arm 55 also loose on shaft 23, having a hub 56 rotatably mounted in bearing 25 of housing cover 40 26. The hub 56 of planet arm 55 is interlocked with a ratchet wheel 57, free on shaft 23. A pawl 58 (Figs. 1 and 3) adapted to engage ratchet wheel 57, is operated by a solenoid 59 carried by a bracket 60 supported on rods 28. The operation of the solenoid is controlled in part by connections from a feeler plate indicated at C, Figs. 5 and 6, which operates one of three switches included in series with two other switches, in a control circuit to be herein described, the act of making or breaking the circuit causing the solenoid to move the pawl 58, in or out of engagement with the ratchet wheel 57, as will be hereinafter set forth more at length.

The pawl 58 is pivotally mounted on a stud 61 supported at the lower end of arms 62 and 63 suspended from the bracket 60, and is normally held in engagement with ratchet wheel 57 by a tension spring 64 having one end anchored to a spring post 65 on the pawl and its other end anchored to a spring post (not shown) provided on arm 62.

When the pawl 58 is in engagement with ratchet wheel 57, the latter and its co-acting arm 55 are held from turning, permitting the worm 21 to transmit motion to its worm wheel 22 and gears 50, 51 and 52, whereby gear 52 drives sun gear 53, imparting motion to shaft 23 and its affixed sprocket 66. The turning of sprocket 66 drives a chain 67 running over the sprockets 68 and 69, Fig. 1, thereby driving the pulleys 70 and 71 and their respective conveyor belts 10 and 11. Pulley 70 is mounted on a shaft 72 and pulley 71 is mounted on a shaft 73 having a gear 74 meshing with a gear 75 mounted on a shaft 76. Shaft 76 is also provided with a

sprocket 77 driving a chain 78 running over a sprocket 79 on shaft 80, the latter having a pulley 81 driving a top tension belt 82 running over a pulley 83 on a shaft 84 supported by an adjustable bracket 85. Bracket 85 is adjustable to provide means for conforming the tension to the different heights of loaves to be sliced.

The release of pawl 58 from ratchet wheel 57 results in the incapacitation of the driving means to the belts 10, 11 and 82, for while the worm 21 drives worm wheel 22 and gears 50, 51 and 52, the latter travel around the now stationary sun gear 53 so that the arm 55 and its interlocked ratchet wheel 57 merely revolve idly about the stationary shaft 23, thus no motion will be transmitted to sprocket 66 and its driven members.

The loaves of bread to be sliced are placed on the horizontal conveyor 10 which advances them on to the inclined conveyor 11 leading to the reciprocating slicer knives 12 of the slicer unit. 20 The leading loaf is pushed through the knives 12 by the following loaves and passes over the bridge 90, Figs. 1, 2 and 5 into the path of the conveyor flights 91, Fig. 5, which propel the sliced loaves in timed relation, to a wrapping machine 25 (not shown) by means to be presently described.

The conveyor chains 93, Figs. 5 and 6, are provided at spaced intervals with special links having extending lugs 94 adapted to receive and support the flights 91. The front and rear chains 93 30 run over intermittently driven sprockets 95 and 96 respectively, and over idler sprockets 97 mounted on a shaft 98 supported by the side frames 99 and 100. Sprockets 95 and 96 are secured to the ends of a sleeve 101 provided with 35 bushings 102 having a running fit upon, and to be turned by, a continuously rotating shaft 103 driven by any suitable means from a wrapping machine, not shown. Shaft 103 is supported in bearings (not shown) of the outer side frames 40 99 and 100 of the slicing machine.

The hub of sprocket 95 carries a pin 104 adapted to be engaged and driven by a spring tensioned pawl 105 fulcrumed on a stud 106 of a driving arm 107 secured on shaft 103. The drive 45 104-105 remains engaged as long as a continuous and properly timed flow of loaves issue from the slicer, but when an interruption occurs, the drive will be automatically disengaged, stopping the rotation of sprockets 95 and 96 and consequently the travel of conveyor chains 93. The disengagement of the drive is desirably accomplished by means of a roller 108, carried by a trip arm 109, which will project into the path of the pawl 105 ready to engage the inclined portion 55 110 of the same, when an interruption occurs in the continuous flow of the loaves, thereby tripping said pawl and releasing it from pin 104.

The arm 109 is secured to one end of a pivot shaft 111 mounted on trunnions 112, one of 60 which is supported by the frame 99, Fig. 6, and the other carried by a plate 113 suspended from one of the support bars 114. Bars 114 are secured to tie bars 115 and 116 (Fig. 5), being square in cross-section and turned at their ends to fit 65 suitable hubs provided on the frames 99 and 100 (not shown). The bar 115 supports a U-shaped bracket 117 having legs 118 and 119 providing means for securing the same to said bar. The members 118 and 119 are provided with trunnions 120 carrying a comparatively short pivot shaft 121 carrying a fixed arm 122 connecting to a trip arm 123. Arm 123 terminates in a link 124 connecting to an arm 125 secured to pivot shaft 111, and arm 125 carries a stud 126 equipped 70 75

with an adjustable counter-weight 127 which tends to normally retain the trip arm 123 in its up-position.

The bars 114 support a table 130 and an adjustable plate 131, U-shaped in cross-section and partly overlying the table 130. A U-shaped bridge plate 132, also supported by bars 114, is mounted so as to allow a clearance for a sliding fit of plate 131. Plate 131 supports a hinge 133 connecting to an inclined trip plate 134 equipped with a roller 135 adapted to depress trip arm 123. Plate 131 is provided with a rectangular opening 136 permitting up and down movement of the plate 134. Plate 131 is also provided with elongated slots 137 permitting lateral movement of said plate and its attached trip plate 134, thus providing means for setting the trip plate to accommodate the different sizes of loaves, and when correctly set the plate may be locked in position by screws 138.

At the start of a run, the plate 131 is adjusted so that the loaves issuing from the slicer will depress plate 134 when they are approximately one inch clear of the bridge 90, Fig. 5. The descent of plate 134, acts, by means of roller 135, to depress the trip arm 123, the final one-eighth inch of travel of the latter closing the circuit of a normally open "Microswitch" 140. The descent of arm 123 also lifts the arm 109 and its roller 108 out of the path of the pawl 105, thereby permitting the pawl to engage pin 104 and drive the conveyor chains 93 during the next cycle of shaft 103.

The switch 140 is wired in series with two other Microswitches 141 and 142 to the solenoid 59. Switch 141, which is also normally open is controlled by an adjustable cam 143 which rotates only when the conveyor chains 93 are in motion. The normally closed switch 142 is controlled by a cam 144 adjustably attached to the continuously rotating shaft 103, and imparts motion to the delivery conveyor chains 93 when a load overlies the trip plate 134.

The cam 143, being adjustably attached to the clutch sprocket 95, is provided with arcuate slots allowing movement of the cam to a position so that the roller 145, on the switch lever 146, rests about one-sixteenth of an inch from the edge of the raised portion 147 of the cam. This set-up of the roller is made when the pawl 105 has just been disengaged from the pin 104, leaving sprocket 95 in its stationary position, the cam 143 being then clamped in position by means of bolts 148. A set screw 149, carried by lever 146, is adjusted so as to engage a leaf spring 150 of the switch 141, opening the circuit of the same at the time the roller 145 leaves the high portion of the cam.

The cam 144, at the other end of shaft 103, is set in such relation with the cam 143, that a roller 151 on a switch lever 152 will leave its position on the high portion 153 of cam 144 and close the circuit of switch 142 shortly after the circuit of the switch 141 has been opened. In this manner no current will flow to the solenoid 59, and the same remains de-energized, thereby preventing unnecessary interruptions in the loaf-feeding action of the feed-in belts 10 and 11 during normal operation. The lever 152 is secured on a stud 155 supported by a flanged sleeve 156 carried by plate 113, said sleeve having a threaded portion to receive a nut 157 acting to retain it in place. A collar 158, fixed on the other end of stud 155, is provided with a set screw 159 which is adapted to actuate a leaf spring 160 of switch 142, as the screw 159 sweeps around.

To regulate the action of the delivery conveyor

93 so as to handle different width loaves, the cam 143 is provided with an adjustable cam part 161, of the same outside diameter as the high portion 147 of said cam. In setting this adjustable cam part, the chains 93 are advanced by turning shaft 103, until one of the flights 91 passes over and clears plate 134 by approximately one-half inch. At this point, a clamp screw 162 of cam 143 is loosened, and the adjustable cam part 161 is moved until it is about to engage the roller 145, 10 said cam then being clamped in position by tightening screw 162. It should be remembered that the plate 131 also has to be adjusted in or out for different width loaves so as to maintain the desired relation between bridge 90 and the tripping 15 of plate 134, as hereinbefore described.

For wide loaves, the cam 161 is moved in a counterclockwise direction, shortening the period of time during which the switch 141 remains closed, and for narrow loaves the cam is moved 20 in a clockwise direction, increasing the period of time the switch remains closed. In this manner the belts 10 and 11 remain stationary for a longer or shorter period of time, depending on the setting of cams 143 and 161. During normal operation of 25 the machine, that is, when the loaves continue to issue from the bridge 90 in properly timed relation, the clutch 104-105 will remain engaged and will drive the flights 91. The loaves drop successively from the bridge, and each loaf rests 30 momentarily until the flight engages it and propels it over the trip plate 134, depressing the same and closing switch 140. In the meantime cam surfaces 147 and 161 hold switch 141 closed and cam surface 153 holds switch 142 open. In this 35 manner, there will be an interruption in the flow of current to the solenoid 59, leaving the same de-energized, whereby the pawl 58 will remain engaged with ratchet 57, permitting the planetary gearing to drive the feed-in belts 10 and 11. 40

If a loaf should happen to issue from bridge 90 with enough speed to trip and rest on plate 134, its co-acting switch 142 will be closed and switch 141 will also be closed by means of its cam. The cam surface 153 in this case would not have had 45 time to open its switch 142, so that all the switches will be closed momentarily, whereby a flow of current will reach solenoid 59, energizing the same and disengaging its pawl and ratchet arrangement. The drive of belts 10 and 11 will 50 therefore remain motionless until switch 142 is again opened, whereupon the solenoid will be de-energized, permitting the pawl to engage the ratchet and thereby allowing the gearing to 55 impart motion to the feed-in belts.

If a loaf should be improperly timed, or arrive late, the trip plate 134 will remain in its inclined position holding roller 108 in the path of pawl 105, disengaging the same from pin 104, and thus stopping the drive of the conveyor 93 60 during the remaining cycle of shaft 103. In the meantime, the feed-in belts 10 and 11 have advanced the loaves so that the leading loaf which was late, will be advanced on to trip plate 134, closing switch 140. The plate 134 in descending causes arm 109 carrying knock-out roller 108 to ascend, permitting the pawl 105 to again engage pin 104 and impart motion to the conveyor 93. In the meantime, switch 141, by 65 means of its cam, is closed and inasmuch as cam surface 153 would not be in position to open switch 142, a flow of current will reach the solenoid, thus stopping the motion imparted to the feed-in belts 10 and 11. 70

What is claimed is:

1. In an apparatus of the class described, a slicer mechanism, a travelway through said mechanism, an in-feed conveyor mechanism for feeding articles to be operated upon, such as loaves, in substantially continuous, contiguous succession through said slicer, means operating normally to actuate said in-feed conveyor mechanism constantly, an outbound conveyor mechanism adapted to receive, to space and to forward, sliced articles from said slicer, means operating normally to actuate said outbound conveyor mechanism constantly when said articles pass from said slicer with normal regularity, and a unitary sensing and incapacitating mechanism, including a feeler disposed in said travelway near the discharge region between the slicer mechanism and outbound conveyor mechanism and adapted to be engaged with each loaf passing said discharge region, and connections leading from said incapacitating means for the in-feed conveyor mechanism and the outbound conveyor mechanism respectively, whereby said feeler at various positions thereof causes incapacitation of one of said conveyor mechanisms independently of the other, and means to adjust said feeler bodily lengthwise of said conveyor and with relation to its associated instrumentalities to compensate for variations in loaf sizes.
2. In an apparatus of the class described, a slicer mechanism, a travelway through said mechanism, an in-feed conveyor mechanism for feeding articles to be operated upon, such as loaves, in substantially continuous, contiguous succession through said slicer, means operating normally to actuate said in-feed conveyor mechanism constantly, means to incapacitate said in-feed conveyor mechanism upon occurrence of a disconformity in the regularity of travel of said articles into and through said slicer, an outbound conveyor mechanism adapted to receive, to space and to forward sliced articles from said slicer, means operating normally to actuate said outbound conveyor mechanism constantly when said articles pass from said slicer with normal regularity, means to incapacitate said outbound conveyor mechanism upon occurrence of a predetermined disconformity in said regularity last named, and a unitary sensing and incapacitating mechanism, including a feeler disposed in said travelway near the discharge region between the slicer mechanism and outbound conveyor mechanism and adapted to be engaged with each loaf passing said discharge region, and connections leading from said incapacitating means for the feed conveyor mechanism and for the outbound conveyor mechanism respectively whereby said feeler, in various positions thereof, causes incapacitation of both of said conveyor mechanisms, and at times causes incapacitation of one of said conveyor mechanisms, independently of the other, and means to adjust said feeler bodily lengthwise of said conveyor and with relation to its associated instrumentalities to compensate for variations in loaf sizes.
3. Apparatus of the class described, comprising a slicer mechanism, an articleway leading through said mechanism, in-feed and outbound conveyor devices for feeding articles, such as loaves of bread, into and away from said slicing mechanism and cooperating to advance said articles in predetermined arrangement for delivery to another mechanism, such as a loaf-wrapper mechanism, means to incapacitate at least one of said conveyor mechanisms upon oc-

currence of a predetermined disconformity in the approach of one or more of said articles to the outbound conveyor mechanism, and a sensing mechanism with connections adapted to make said incapacitating means effective upon occurrence of said disconformity, said sensing mechanism being adjustable bodily lengthwise of said conveyor to compensate for variations in loaf size, while maintaining its operative relation to the associated instrumentalities.

4. Apparatus of the class described, having the features claimed in claim 3, in which said incapacitating mechanism is common to said in-feed and outbound conveyor mechanisms and includes a primary control means adapted to be actuated by said sensing mechanism device exclusively when in predetermined positions thereof, for incapacitating the in-feed conveyor mechanism, to halt delivery of articles to said slicer mechanism, and includes also an electrically operated secondary control means adapted to be actuated by said sensing mechanism exclusively when said feeler device is free from contact with any article in said articleway, said control device acting to halt operation of said outbound conveyor, said electrically operated secondary control means including flexible electrical conductors adapted to maintain the electrical circuits in the several adjustive positions of the parts.

5. Apparatus of the class described, having the features claimed in claim 3, in which said incapacitating mechanism is common to said in-feed and outbound conveyor mechanism and includes a primary control means adapted to be actuated by said sensing mechanism device exclusively when in predetermined positions thereof, for incapacitating the in-feed conveyor mechanism, to halt delivery of articles to said slicer mechanism, and includes also a secondary control means adapted to be actuated by said sensing mechanism exclusively when said feeler device is free from contact with any article in said articleway, said secondary control means acting to halt operation of said outbound conveyor, said primary control means comprising an electromagnetic device included in series in a control circuit with a plurality of electric switches movable respectively to make and break said control circuit, to incapacitate said actuating mechanism for the infeed conveyor mechanism, said control circuit having electrical conductors adapted to maintain the electrical circuit in appropriate working condition in the several adjustive positions of the parts and said secondary control means including means operated in part by the conveyor actuating mechanism, and in part by supplemental members connected with said sensing mechanism, to make said last-named incapacitating mechanism effective and ineffective selectively, according to the position of said primary and/or secondary control means, singly or in combination.

6. Apparatus of the class described, comprising a slicer mechanism, an articleway leading therethrough, an infeed conveyor, a loaf wrapper, an outbound conveyor leading from said slicer to said wrapper, means to incapacitate said conveyors selectively upon occurrence of certain predetermined disconformities in the loaf-feed, a sensing mechanism with connections adapted to make said incapacitating means effective, said connections comprising an electro-magnetic device included in a control circuit with a plurality of electric control switches, a sun-and-planet differential gear system controlled by said electro-magnetic device, and acting to operate said

infeed conveyor when made effective by said electro-magnetic device, and a mechanical means normally effective to couple said outbound conveyor for operation by said wrapper mechanism, 5 said coupling means being incapacitated by said sensing mechanism in the absence of any loaf from due engagement with said sensing mechanism, said outbound conveyor being coupled at regular cyclical intervals independently of the 10 operation of said electro-magnetic device, and also being recoupled when said sensing mechanism senses the presence of a loaf in position for conveyal to said wrapper.

7. In a loaf feed control of the class described, 15 in which a feeler operates at a sensing station in the path of sliced loaves passing along a travel-way, from which station they are advanced to a wrapping mechanism by an outbound conveyor normally actuated in time with the wrapping 20 mechanism, and to which travelway the unsliced loaves are fed by an inbound conveyor through a slicer, and are thence forwarded to the wrapping mechanism in spaced apart succession by flights on said outbound conveyor, said feeler being 25 biased into said path normally, and adapted to be depressed by a superimposed sliced loaf in the travelway: mechanism including a normally closed clutch, for normally actuating said inbound conveyor: an electrical control circuit including 30 an electromagnetic device and a first electrical switch to throw out said clutch; means actuated by said feeler, when depressed by the presence of a sliced loaf to close said first switch, thereby to operate said electromagnetic device to 35 render said clutch ineffective to drive said inbound conveyor; mechanism including another clutch device for actuating said outbound conveyor; means biased normally to couple said second clutch device, making effective said outbound conveyor drive; a device operated by said feeler when the bias of said feeler is made effective by the absence of a sliced loaf throughout the remainder of a cycle, to render said last-named clutch ineffective to transmit driving 40 power to said outbound conveyor, during a succeeding cycle.

8. In a loaf feed control of the class described, 45 in which a feeler operates at a sensing station in the path of sliced loaves passing along a travel-way, from which station they are advanced to a wrapping mechanism by an outbound conveyor normally actuated in time with the wrapping mechanism, and to which travelway the unsliced loaves are fed by an inbound conveyor through a 50 slicer, and are thence forwarded to the wrapping mechanism in spaced apart succession by flights on said outbound conveyor, said feeler being biased into said path normally, and adapted to be depressed by a superimposed sliced loaf in the travelway: mechanism including a normally closed first clutch for normally actuating said outbound conveyor; means biased normally to a position for throwing out said first clutch cyclically; means actuated by said feeler, when depressed 55 by a superimposed sliced loaf, to convert said last named bias and make said first clutch effective to drive said outbound conveyor; mechanism coordinated with the wrapping mechanism, including a second clutch device for actuating said inbound conveyor; means biased normally to throw in said second clutch device, making effective said inbound conveyor drive; an electromagnetic device adapted to operate said second clutch device and included in an electrical 60 control circuit with an electric switch operated

by said feeler to close said control circuit through said electromagnetic device when the bias of said feeler is controverted by a superimposed loaf, thereby to throw out said second clutch, and moving to break said circuit when the bias of said feeler becomes effective in the absence of a loaf, thereby to render the second clutch effective to transmit driving power to said inbound conveyor. 5

9. A loaf feed control of the class described, in which a feeler operates at a sensing station in the path of sliced loaves passing along a travel-way, from which station they are advanced to a wrapping mechanism by an outbound conveyor normally actuated in time with the wrapping mechanism and to which travelway the unsliced loaves are fed by an inbound conveyor through a slicer, and are thence forwarded to the wrapping mechanism in spaced succession by flights on said outbound conveyor, said feeler being 20 biased into said path normally, and adapted to be depressed by a superimposed sliced loaf in the travelway: said feed control being further characterized by the provision of a plate on which said feeler is mounted for adjustment 25 bodily, lengthwise of said outbound conveyor, to compensate for variations in loaf size, and means to hold said plate in adjusted position.

10. A loaf feed control of the class described, in which a feeler operates at a sensing station in the path of sliced loaves passing along a travel-way, from which station they are advanced to a wrapping mechanism by an outbound conveyor normally actuated in time with the wrapping mechanism and to which travelway the unsliced loaves are fed by an inbound conveyor through a slicer, and are thence forwarded to the wrapping mechanism in spaced succession by flights on said outbound conveyor, said feeler being 30 biased into said path normally, and adapted to be 35 depressed by a superimposed sliced loaf in the travelway: said feed control being further characterized by the provision of a plate adjustable bodily lengthwise of the conveyors, and on which said feeler is mounted for such bodily adjustment lengthwise of the conveyors, to compensate for variations in loaf size, and means to hold said plate in adjusted position relatively to said conveyors and in continued coordination therewith. 50

11. In a loaf feed control of the class described, in which a feeler operates at a sensing station in the path of sliced loaves passing along a travel-way, from which station they are advanced to a wrapping mechanism by an outbound conveyor normally actuated in time with the wrapping mechanism, and to which travelway the unsliced loaves are fed by an inbound conveyor through a slicer, and are thence forwarded to the wrapping mechanism in spaced apart succession by flights on said outbound conveyor, said feeler being biased into said path normally, and adapted to be depressed by a superimposed sliced loaf in the travelway: mechanism including a normally closed first clutch for normally actuating said outbound conveyor; means biased normally to a position for throwing out said first clutch cyclically; means actuated by said feeler, when depressed by a superimposed sliced loaf, to controvert said last named bias and make said first clutch effective to drive said outbound conveyor; mechanism coordinated with the wrapping mechanism, including a second clutch device for actuating said inbound conveyor; means biased nor- 70 75

mally to throw in said second clutch device, making effective said inbound conveyor drive; an electromagnetic device adapted to operate said second clutch device and included in an electrical control circuit with an electric switch operated by said feeler to close said control circuit through said electromagnetic device when the bias of said feeler is controverted by a superimposed loaf, thereby to throw out said second clutch, and moving to break said circuit when the bias of said feeler becomes effective in the absence of a loaf, thereby to render the second clutch effective to transmit driving power to said inbound conveyor; a second normally open switch included in said control circuit; and means operated cyclically whenever the outbound conveyor is in operation, to close said last-named switch, thereby to permit completion of the control circuit and stoppage of the inbound conveyor in the event that the feeler is depressed for an undue period by the presence of loaves thereon.

12. In a loaf feed control of the class described, in which a feeler operates at a sensing station in the path of sliced loaves passing along a travelway, from which station they are advanced to a wrapping mechanism by an outbound conveyor normally actuated in time with the wrapping mechanism, and to which travelway the unsliced loaves are fed by an inbound conveyor through a slicer, and are thence forwarded to the wrapping mechanism in spaced apart succession by flights on said outbound conveyor, said feeler being biased into said path normally, and adapted to be depressed by a superimposed sliced

loaf in the travelway; mechanism including a normally closed first clutch for normally actuating said outbound conveyor; means biased normally to a position for throwing out said first clutch cyclically; means actuated by said feeler, when depressed by a superimposed sliced loaf, to controvert said last named bias and make said first clutch effective to drive said outbound conveyor; mechanism coordinated with the wrapping mechanism, including a second clutch device for actuating said inbound conveyor; means biased normally to throw in said second clutch device, making effective said inbound conveyor drive; an electromagnetic device adapted to operate said second clutch device and included in an electrical control circuit with an electric switch operated by said feeler to close said control circuit through said electromagnetic device when the bias of said feeler is controverted by a superimposed loaf, thereby to throw out said second clutch, and moving to break said circuit when the bias of said feeler becomes effective in the absence of a loaf, thereby to render the second clutch effective to transmit driving power to said inbound conveyor; a second normally open switch included in said control circuit to interpose a cyclical element into the circuit operations, a third switch, normally closed, in the control circuit, and means to open the last-named switch cyclically to incapacitate the electromagnetic device from operating to stop the outbound conveyor when loaves are ready to be forwarded.

ROBERT J. BEUTEL.
